GAS COOKSTOVE WITH COMBINED TOP PILOT AND SIMMER BURNER

Herbert M. Reeves, Kankakee, Ill., assignor to
Florence Stove Company, Gardner, Mass., a
corporation of Massachusetts

Application May 4, 1948, Serial No. 25,013

5 Claims. (Cl. 126—39)

1

The invention pertains to gas cook stoves and has particular reference to a cooking top of the type having a plurality of burners arranged in a convenient group, usually rectangular in form, with a lighting system including a pilot burner disposed centrally of the group. In conventional ranges the cooking top comprises a sheet metal top plate which is imperforate except for the openings for the top burners and for the pilot burner. As is well known, the latter burns continuously and gives off a substantial amount of heat which is wasted through dissipation to the top plate and to the atmosphere above the plate.

The primary object of the present invention is to provide for the effective utilization of the heat of the pilot burner so as to connect it to a simmer burner, through the provision of an auxiliary utensil-supporting grate overlying the pilot burner and by especially constructing the cooking top so as to minimize dissipation of heat thereto.

A further object is to provide a cooking top structure having main utensil-supporting grates overlying the top burners and an auxiliary grate overlying the pilot or simmer burner, in an arrangement such that the main grates cooperate with the auxiliary grate in supporting a utensil above the simmer burner.

The objects of the invention thus generally stated together with other and ancillary advantages are attained by the construction and arrangement shown by way of illustration in the accompanying drawing in which:

Figure 1 is a fragmentary perspective view of the top section of a gas cook stove embodying my invention.

Fig. 2 is a fragmentary sectional view on an enlarged scale taken approximately in the plane of line 2—2 of Fig. 1.

Fig. 3 is a fragmentary plan view of the central portion of the cooking top showing the special construction of the top plate whereby the conduction of heat to the top plate is minimized, the auxiliary utensil-supporting grate being shown in broken lines.

The improved cooking top illustrated comprises a generally flat top plate 7 of sheet steel having flat peripheral edge portions adjoined to the top edges of the front and side panels 5 and 6 of a cookstove. Four burner openings 8 are formed in the plate in a generally rectangular group each opening having a top burner 9 disposed centrally thereof. The utensil-supporting grates 10 are preferably in the form of circular disks 11 of a diameter somewhat smaller than the openings 8, and each is provided with a plurality of radial arms 12 (herein three) resting upon the top plate externally of the holes 8 and preferably interengaging with the plate through the medium

2

of small slots receiving depending portions at the outer ends of the arms. It will be observed from Fig. 1 that certain of the arms 12 of the four grates 10 project toward and in alinement with each other, and that the tops of the grates are disposed in a common plane in a vertically offset relation to the top plate 7.

The cooking top further comprises a lighting system including the usual pilot burner 13 and lighter tubes 14 extending from the several cooking top burners to a central point adjacent the pilot burner. As shown, the pilot burner has an inner frusto-conical cap or hood 15 disposed so as to encircle the base of the flame, the top of the hood being open for the passage of the flame into the space between the lighter tubes. An outer housing 16 encloses the pilot burner and serves to support the inner end of the tubes, this housing being suitably secured to the underside of the top plate.

The top plate has a central hole 17 directly overlying the pilot burner, substantially in the conventional manner. However, in the present instance the hole 17 is formed centrally of the upper portion of a shallow dome formed in the top plate and generally designated 18. Overlying the dome and in closely spaced relation to the hole 17 is an auxiliary utensil-supporting grate 19 made generally similar to the grates 10 but of much smaller size. It comprises a circular disk 20 having a plurality of radial supporting arms 21 with depending outer ends resting upon the cooking top plate externally of the dome 18. The arms 21 are preferably provided with lugs for entry into positioning slots 22 in the top plate (Fig. 3).

In the present instance, the shallow dome 18 is pressed upwardly out of the top plate so as to provide an annular sloping wall portion 23 terminating at its upper edge in a flat annulus 24, and a smaller sloping wall portion 25 terminating in a flat top portion 26 which contains the hole 17, centrally of the dome, and is disposed in closely spaced relation to the auxiliary grate 19.

To minimize the conduction of heat from the pilot flame to the cooking top and to permit of the application of such heat to a utensil supported on the grate 19, the cooking top is perforated in the region encircling the hole 17. As herein shown, the annulus 24 of the dome 18 is formed with an annular series of holes 27 in a substantial contiguous series. These holes underlie the peripheral portion of the grate 19 and permit the passage of hot gas upwardly against the peripheral portion of the grate. Of course the major portion of the gases pass directly upward through the hole 17 for escape outwardly between grate and the top 26 of the dome. The holes 27, being spaced a somewhat greater distance from the grate, provide for the relatively

free passage of the gases upwardly and outwardly beneath the grate and the bottom of the utensil, the latter usually being of a diameter substantially in excess of that of the grate.

Reference has been made above to the fact that certain of the arms of the grates 10 project toward and are alined with each other. In this connection, it will be observed that the auxiliary grate 19 is disposed in the same plane as the grates 10 and that the arms 21 thereof coact with the arms 12 of the grates 10 so as to provide a firm support for large utensils placed centrally over the grate 19.

Experience has shown that by the construction provided the heat of the pilot burner, which is normally wasted through dissipation to the atmosphere and the cooking top, is effectually utilized. Thus it has been found that it is possible to maintain one quart of water at a temperature of 150° F and this at no extra cost. Similarly it has been found that two quarts of water placed upon the auxiliary grate overnight can be raised to a temperature of 140° F.

I claim as my invention:

1. In a gas cook stove having a cooking top plate with a plurality of burner openings, a burner for each opening, utensil-supporting grates overlying the burner openings, a lighter system for said top burners including a pilot burner, said top plate having a hole directly overlying the pilot burner, and an auxiliary utensil support having a solid section in the body thereof at least as large as said hole, said support being removably supported on the top plate above said hole and disposed substantially in the plane of the top burner grates with said solid section located directly over said hole to afford protection for said pilot, said cooking top plate being perforated around said pilot burner hole to permit the passage of hot gases against the peripheral portion of the auxiliary grate and serving to minimize the dissipation of heat from the pilot burner to the top plate.

2. A gas cook stove having a generally flat cooking top plate with flat peripheral edge portions adjoined to the top edges of the front and side panels of the stove, a plurality of burner openings formed in said plate, burners in said openings, utensil-supporting grates overlying said openings and supported on said plate, a lighter system for said burners including a pilot burner disposed beneath the top plate, and an auxiliary utensil-supporting grate overlying the pilot burner and supported on said plate, said top plate having a raised central portion underlying the auxiliary grate so as to form a shallow dome having an upper portion disposed contiguous to said auxiliary grate, and said dome being apertured centrally thereof and above said pilot burner and also having an annular series of perforations underlying the peripheral portion of said auxiliary grate.

3. A gas cook stove having a cooking top plate with a plurality of burner openings, burners in said openings, utensil-supporting grates overlying said openings and a lighter system for said burners including a pilot burner disposed beneath the top plate, said top plate having a raised portion overlying said pilot burner and forming a shallow dome having a hole in its upper central portion directly above the pilot burner, and a utensil-supporting grate removably seated on the top plate above and in closely spaced relation to the dome, said last mentioned grate having a solid portion at least as large as

said hole and disposed directly over said hole to protect said pilot burner, said dome having an annular portion disposed in a plane below said hole and apertured for the passage of hot gases upwardly against the peripheral portion of the auxiliary grate.

4. A gas cook stove having a top plate with a plurality of burner openings arranged in a generally rectangular group, a top burner for each opening and utensil-supporting grates overlying each opening and comprising disks having radial arms supporting said disks above and in vertically offset relation to the top plate, a lighter system for said burners including a pilot burner disposed substantially centrally of said group of burner openings, said top plate having a hole directly above the pilot burner, and an auxiliary utensil-supporting grate overlying the pilot burner hole and comprising a disk having arms resting upon the top plate and supporting the auxiliary grate in the plane of the top burner grates, certain of the arms of the top burner grates cooperating with the arms of the auxiliary grate to support a large size utensil, and said top plate being perforated in the region surrounding said pilot burner hole.

5. A gas cook stove having a generally flat plate defining the top surface of the stove, said plate being formed with a plurality of main burner openings arranged in a group, a main burner disposed in each of said openings, independent utensil-supporting main grates overlying the respective burner openings, said main grates having arms thereon extending radially outwardly therefrom in generally parallel relation to said plate, the outer ends of said arms being turned downwardly to interengage with said top plate and support the grates in vertically spaced relation to the top plate and to restrain the grates against lateral movement, a lighter system for said burners including a pilot burner disposed below said top plate and in spaced relation to the main burner openings, said top plate defining a hole directly above the pilot burner, and an auxiliary utensil-supporting grate comprising a solid generally flat disk having radially extending arms with their end portions turned downwardly to interengage with the top plate to support said disk directly over said pilot burner hole and to restrain it against lateral movement, the turned down end portions of said arms being dimensioned to support the disk and arms of the auxiliary grate in a common plane with the main grate, the arms of the auxiliary grate extending to the vicinity of said main grates to form a broad seat adapted to support a large utensil over said pilot burner to be heated thereby.

HERBERT M. REEVES.
